(57) **CLAIM**

The ornamental design for a case for housing a paper towel, as shown and described.

DESCRIPTION

FIG. 1 is a front elevational view of a case for housing a paper towel showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a horizontal cross-sectional view thereof, taken along line I—I of FIG. 1;

FIG. 8 is a vertical cross-sectional view thereof, taken along line II—II of FIG. 3;

FIG. 9 is an additional vertical cross-sectional view thereof, taken along line II—II of FIG. 3, but with the adaptor omitted;

FIG. 10 is a top, front, and left side perspective view thereof; and,

FIG. 11 is a top, front, and left side perspective view thereof, with the broken-line disclosure being for illustrative purposes only and forming no part of the claimed design.
